UNITED STATES PATENT OFFICE.

LEROY S. WHITE, OF WATERBURY, CONNECTICUT.

OVEN-THERMOMETER.

941,667.

Specification of Letters Patent. Patented Nov. 30, 1909.

Application filed June 26, 1909. Serial No. 504,475.

To all whom it may concern:

Be it known that I, LEROY S. WHITE, a citizen of the United States, residing at Waterbury, in the county of New Haven 5 and State of Connecticut, have invented a new and useful Improvement in Oven-Thermometers; and I do hereby declare the following, when taken in connection with the accompanying drawings and the letters of 10 reference marked thereon, to be a full, clear, and exact description of the same, and which said drawings constitute part of this specification, and represent, in—

Figure 1 a front view of an oven thermometer embodying my invention. Fig. 2 a similar view with the dial removed. Fig. 3 a vertical sectional view. Fig. 4 a broken transverse sectional view. Fig. 5 a front view of a modified form of my invention 20 with the dial partially broken away. Fig. 6 a perspective view of a section of one form of expandable strip. Fig. 7 a perspective view of a section of another form of expandable strip.

This invention relates to an improvement 25 in oven thermometers, that is, a device mounted in an oven door and serving to indicate the approximate temperature of the oven, the object of the invention being a simple arrangement of parts which may be 30 readily assembled, and which is comparatively thin so as to occupy but little space; and the invention consists in the construction hereinafter described and particularly 35 cited in the claims.

In carrying out my invention I employ a main plate or flange 2 adapted to be secured to the inside of an oven door 3 in the usual manner. This plate has a central 40 threaded opening 4 to receive a cup or shell 5 externally threaded at its inner end for engagement with the threads of the opening 4 so as to form a tight joint with the plate 2 and completely close the opening. Within 45 the cup is the usual mechanism of an oven thermometer. This preferably consists of a three-armed yoke 6 of such dimensions as to closely fit the interior of the cup so that it will be held therein by friction. Two of the 50 arms will be provided with outwardly extending lugs 7 which enter notches 8 formed in the dial 9, this dial being held in place by a ring 10 which supports a glass 11 which in turn is held in place by a friction collar 12

fitting the outside of the dial and overlapping the outer edge of the glass. 55

As shown in Figs. 1, 2 and 3 of the drawings the pointer 13 is mounted on a central shaft 14 carrying a pinion 15 which is in mesh with a segmental rack 16 mounted in 60 the central arm 17. This rack is connected by a link 18 with one end of the metal strip 19, the other end of which is connected with the yoke, the expansion and contraction of this strip moving the rack so as to turn the 65 pointer.

Instead of having the pointer arranged in the center of the dial, it may be eccentrically mounted as shown in Fig. 5 of the drawings, in which case the rack and pinion will be 70 omitted, and the pointer mounted on a shaft 20 which carries a cam 21 corresponding to a portion of the rack 16 and to which the link 18 is connected. The strip 19 may be a bi-metal strip as shown in Fig. 6 of the 75 drawings, or it may consist of two independently formed strips 22 and 23 secured together by a series of rivets 24 as shown in Fig. 7 of the drawings, these being common forms of strips for oven thermometers as the 80 action of heat on the different metals will cause the strip to straighten or bend so as to move the pointer in one direction or the other.

It will be noted that all the mechanism is 85 mounted in one cup or shell, and the closed end of that cup or shell closes the opening in the plate or flange which is provided to secure the thermometer to the oven door. I thus avoid all rivet holes in the case so 90 that the possibility of leakage of steam or gases from the oven is avoided. The cup or shell may be threaded to a greater or less extent so as to be capable of being turned into the oven more or less as is required. 95

I claim:—

1. In an oven thermometer, the combination with a cup the external side walls of which are threaded, of a flange adapted to be secured to the inner face of an oven door 100 and formed with a threaded opening corresponding to the diameter of said cup which is adapted to be turned into it, an expandable strip mounted in the case and a pointer operated thereby. 105

2. In an oven thermometer, the combination with a plate or flange having a threaded opening, of a cup externally threaded at

its inner end, a three-armed yoke frictionally held in said cup, a pointer mounted in said yoke, an expansible strip connected with the yoke and with the pointer, said yoke formed with outwardly projecting lugs, and a dial having notches for engagement with said lug, and means for holding the dial in position.

In testimony whereof, I have signed this specification in the presence of two subscribing witnesses. 10
